UNITED STATES PATENT OFFICE.

SILAS B. RUSSELL, OF ST. LOUIS, MISSOURI, ASSIGNOR TO PARKER-RUSSELL MINING & MANUFACTURING COMPANY, OF ST. LOUIS, MISSOURI, A CORPORATION OF MISSOURI.

RECUPERATIVE FURNACE.

1,251,426.

Specification of Letters Patent. Patented Dec. 25, 1917.

Application filed January 15, 1917. Serial No. 142,431.

To all whom it may concern:

Be it known that I, SILAS BENT RUSSELL, a citizen of the United States, residing at St. Louis, Missouri, have invented a certain new and useful Improvement in Recuperative Furnaces, of which the following is a full, clear, and exact description, such as will enable others skilled in the art to which it appertains to make and use the same.

This invention relates to recuperative furnaces, and particularly to recuperative furnaces of the type provided with a gas producer or generator.

One object of my present invention is to provide a recuperative furnace of the general type referred to which is equipped with means of novel construction for heating the primary air and injecting said heated primary air mixed with steam into the fuel chamber of the gas producer in such a manner that there is little tendency for the fuel to clinker or the fuel grate to burn out.

Another object is to provide a recuperative furnace that is equipped with a novel means for heating the primary air that is supplied to the producer, said means being so designed that the furnace as an entirety is compact and easy to build.

And still another object is to provide a gas bench of novel design, in which the primary air is drawn through openings formed in the front wall of the furnace, then circulated through passageways that are heated by the waste fire gases escaping from the combustion chamber, and thereafter injected into the fuel chamber of the producer at a number of separated points by means of steam jets that are arranged in proximity to ports in the side walls of the fuel chamber, the primary air passageways and the waste gas flues that heat the same being so constructed that there is little liability of the escaping fire gases mingling with the primary air. Other objects and desirable features of my invention will be hereinafter pointed out.

While I have herein illustrated my invention embodied in a gas bench, I wish it to be understood that my broad idea is appli-

cable to various other types of recuperative furnaces.

Figure 1 of the drawings is a front elevational view, partly in vertical cross section, of a gas bench constructed in accordance with my invention.

Figs. 2 and 3 are vertical sectional views, taken on the lines 2—2 and 3—3, respectively, of Fig. 1.

Fig. 4 is a fragmentary horizontal sectional view, taken on the line 4—4 of Fig. 1.

Fig. 5 is a detail cross-sectional view, illustrating a slight modification of my invention; and

Fig. 6 is a perspective view of one of the steam jets used to inject the heated primary air into the fuel chamber of the producer.

Referring to the drawings which illustrate a gas bench constructed in accordance with my invention, A designates the fuel chamber of the gas producer of the bench, B designates the retorts, C the combustion chamber and D horizontally-disposed fire gas flues through which the waste gases from the combustion chamber travel in escaping to the uptake flue or chimney flue E, as indicated by the arrows in Fig. 3. The fire gas flues D are surrounded by air passageways 1 through which the secondary air circulates, so that said secondary air will be heated before it is admitted to the combustion chamber C, as indicated by the arrows in Fig. 1, and the furnace is also provided with means of novel construction for heating the primary air and injecting it mixed with steam into the fuel chamber A of the gas producer. In the form of my invention herein shown said means consists of horizontally-disposed fire gas flues D' that are arranged at the opposite sides of the fuel chamber A of the producer beneath the fire gas flues D, primary air passageways 2 that surround the fire gas flues D' and steam jets or injecting nozzles 3 arranged in alinement with ports 4 formed in the side walls of the fuel chamber A of the producer, either above the fuel grate F, as shown in Fig. 1, or below said fuel grate,

- as shown in Fig. 5, said steam jets or nozzles serving to inject the heated primary air mixed with steam into the producer and also to induce a circulation of the primary air through the primary air passageways 2. The front end of each of the fire gas flues D' communicates with the front ends of the fire gas flues D that are arranged above same, so that the escaping fire gases will travel through the flue D', as indicated by the arrows in Fig. 3, and thus heat the primary air in the passageways 2 that surround said flue D', and a horizontally-disposed partition 5 is arranged above the flue D', as shown in Figs. 1 and 3, so as to prevent the primary air that circulates through the air passageways 2 from mingling with the secondary air that circulates through the air passageways 1 which surround the flues D. The primary air is admitted to the air passageways 2 through openings 6 in the front wall of the furnace that are provided with closures 7, as shown in Figs. 1 and 2, and each set of steam jets 3 is mounted on a steam supply pipe 8 that extends inwardly through the front wall of the furnace into the space that surrounds the particular fire gas flue D' with which it co-operates. When the furnace is in operation the jets of steam that escape from the nozzles 3 produce sufficient suction in the primary air passageways 2 to cause the primary air to circulate through same. Valves 9 are provided for regulating the supply of steam to the pipes 8, and while any preferred type of steam jet may be used, I prefer to use steam jets of the kind shown in Fig. 6, each of which consists of a four-way pipe fitting 10 having two horizontally-aligned openings into which the supply pipe 8 is screwed, a lateral opening into which a plug 11 provided with an orifice 12 is screwed and an opening on the underside of the same into which a plug 13 is screwed, so as to form a supporting leg for the fitting that rests upon a horizontally-disposed partition 14, as shown in Fig. 2. The partition 14 extends longitudinally along one side of the fire gas flue D' at a point above the inlet opening 6 in the front wall of the furnace through which the primary air is admitted to the air passageways 2 and below the ports 4 through which the primary heated air is injected into the fuel chamber A of the producer, so as to cause the primary air which is admitted to the space or passageway located at the inner side of the flue D' to circulate downwardly underneath said flue, thence upwardly and over same to the ports 4, as indicated by the arrows in Fig. 1. It is immaterial, however, so far as my broad idea is concerned, how the space or passageways 2 through which the primary air circulates are formed, so long as they are of such a character that the primary air will absorb heat from a flue or flues through which the escaping fire gases travel before said primary air reaches the port or ports through which it is injected into the fuel chamber A of the producer. It is also immaterial what particular type of steam jet is used for forcing the heated primary air into the producer, but it is desirable that the steam jets be arranged in such a manner that the heated primary air will be introduced into the fuel chamber of the producer at a number of separated points along the length of said fuel chamber. When the primary heated air, mixed with steam, is introduced into the fuel chamber of the producer through ports 4 in the side walls of said chamber located at a point above the grate F, as shown in Fig. 1, the tendency of the fuel to clinker and the grate to burn out is reduced to a minimum. If desired, however, the heated primary air mixed with jets of steam can be introduced into the producer through ports 4^a formed in the side walls of the producer at points below the grate F, as shown in Fig. 5, the steam supply pipes 8 in such a structure being arranged beneath partitions 14^a in the primary air passageways 2 which are so arranged that the primary air which is admitted to said passageways will circulate upwardly over the fire gas flues D', and thence downwardly across the undersides of said flues to the ports 4^a, as indicated by the arrows in Fig. 5.
- In order to eliminate the possibility of the primary air mingling with the fire gases that escape from the flues D' and also to reduce the cost of manufacturing and erecting the furnace, I prefer to form the top and bottom walls and one of the side walls of each of the flues D', from slabs of refractory material and form the other side of said flue from special blocks or tiles α that are provided with open spaces and partitions which are so arranged that when a plurality of said tiles are arranged end to end, as shown more clearly in Fig. 2, the partitions in the same will co-operate to form the horizontally-disposed partition 14, previously referred to, and the spaces will form part of the passageway through which the primary air circulates.
- While my invention is not limited to a gas bench, it is particularly adapted for use in gas benches on account of the fact that it enables a compact, inexpensive gas bench to be built in which adequate means is provided for preheating the primary air and injecting said heated air mixed with steam into the producer.
- Having thus described my invention, what I claim, and desire to secure by Letters Patent, is:
- In a gas bench, a gas producer, a recuperator

tor provided with a fire gas flue and a space or passageway surrounding said flue through which primary air circulates, one side of said flue being formed by blocks of refractory material having open spaces in the same that form part of said passageway, a division wall between said producer and recuperator that is provided with ports that establish communication between said producer and said primary air passageway, and 10 a steam supply pipe supported by said blocks and provided with steam jets or injecting nozzles arranged in proximity to said ports so as to cause the heated primary air mixed with steam to be supplied to the producer. 15

SILAS B. RUSSELL.
